UNITED STATES PATENT OFFICE

150,006

DESIGN FOR A TUMBLE HEAD TOY

Ernest S. K. Fung, Honolulu, Territory of Hawaii

Application June 27, 1947, Serial No. 139,964

Term of patent 14 years

(Cl. D34—4)

To all whom it may concern:

Be it known that I, Ernest S. K. Fung, a citizen of the United States of America, resident of Honolulu, Territory of Hawaii, have invented a new, original, and ornamental Design for a Tumble Head Toy, of which the following is a specification, reference being had to the accompanying drawing, forming a part thereof wherein:

I claim:

The ornamental design for a tumble head toy, as shown.

ERNEST S. K. FUNG.
